UNITED STATES PATENT OFFICE.

HUGH S. FERGUSON, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

STIRRUP.

1,149,191.

Specification of Letters Patent. Patented Aug. 10, 1915.

Application filed August 27, 1913. Serial No. 786,836.

To all whom it may concern:

Be it known that I, HUGH S. FERGUSON, a citizen of the United States, residing in Whitinsville, county of Worcester, and 5 State of Massachusetts, have invented the following-described Improvements in Stirrups.

The improved stirrup is for use on textile drawing frames or like machines where 10 heavy weights or springs are used for exerting the draft pressure upon the top rolls of the roller head, and the invention consists in the form and structure of such stirrup, adapting it for convenient use in the drawing 15 frame and rendering it capable of production at low cost, all as will be plain to those skilled in the art from the following description.

In the drawing forming part hereof, Figure 1 represents the improved stirrup in use, the top drawing rolls and roller-beam being shown in section; Fig. 2 is a similar view at right angles to Fig. 1.

The figures above referred to represent the 25 top-rolls 1, the saddle 2, the weighting means 3 and roller-beam 4, all in conventional form, it being intended that these parts shall be understood to correspond in relative position to corresponding parts in any drawing 30 frame or machine of the same general characteristics, and that the weighting means 3 shall be regarded as a simple weight or heavy spring or combination of both, according to the usual custom.

The roller-beam 4 is apertured with a slot 35 marked 5, and a stirrup passes through the aperture, being formed with a loop 6 at its upper end for embracing the saddle 2, and with a hook 7 at its lower end for connection with the weighting means 3. The loop 40 6, which is provided with a square top, is of such internal diameter that when the pressure of the weighting means is relieved, the saddle may be withdrawn endwise from 45 within it, and the hook 7 can also be readily disconnected from the said weighting means in an obvious manner. By turning the stirrup to an appropriate position it may be removed entirely from the slot 5 in the roller-beam, the said slot being oblong as indicated 50 and of sufficient length to accommodate the bend of the hook 7 in passing through it.

The stirrup is formed of heavy round

wire or rod stock of substantially uniform 55 diameter from end to end, and the loop 6 at the top, as well as the hook 7 at the bottom, is formed by a simple bending operation. At a predetermined point between the loop and hook, the wire or rod is bent upon itself 60 to form an enlargement, preferably in the form of a loop or eye, marked 8 in the drawings, which enlargement is just above the roller-beam and of sufficiently greater diameter than the width of the slot 5 therein, 65 so that it cannot pass through the slot, especially when in the normal position shown in the drawings. The enlargement thus forms a stop shoulder on the stirrup and is adapted to sustain the weighting means 70 upon the roller-beam on such occasions as when the saddle or top-rolls have been removed for cleaning or other purposes. This position of the said enlargement is indicated by dotted lines in Fig. 2. The point 75 at which the enlargement is formed on the stirrup is selected, so that when in use it will occupy a position just above the roller-beam and at such distance therefrom as will 80 permit a lever, such as indicated at 9 in Fig. 1, to be thrust through the eye to a fulcrum upon the surface of the beam, so that such lever can then be used to lift the weighting means and thereby relieve the pressure upon the saddle. The loop 8 is 85 formed to lie in a plane that is parallel with the drawing rolls, so that it will face the front of the machine and hence be most accessible to the operative for use with the lever, as just mentioned. The enlargement 90 on the stirrup thus serves also as a purchase bearing for a lever or weight relieving means, as well as a stop-shoulder for sustaining the weight when the top rolls are to 95 be removed, and it will be understood that the diameter of the hole or eye in the said enlargement is wide enough to accommodate a weight-relieving lever of ample stiffness for the purpose indicated.

The washer-plate 10 appearing in both 100 figures of the drawing, normally covers the slot 5 in the roller-beam and is desirable for preventing accumulations of lint or dirt therein, although it is not otherwise essential to the operation of the device. It will 105 be evident that when such plate is used, it can be provided with a round hole adapted to receive the round wire stock of which the

stirrup is formed, so that it can be readily passed over the hook-shaped end of the stirrup; and also when such plate is used, the size and shape of the slot 5 above referred to is immaterial so far as the said slot may be used to co-act with the shoulder 9 in sustaining the weight 3. The enlargement 8 will, in any event, rest upon or be supported by the roller-beam, as will be evident.

The particular features which I regard as constituting the essence of my invention, are as follows:

I claim:

15. 1. In a drawing frame or like machine, a stirrup formed of a rod bent upon itself to form an enlargement between its ends and formed at the said ends for connection with a saddle and a weighting means, respectively.

20. 2. In a drawing frame or like machine, a stirrup formed of a rod looped at about its middle to form an eye-enlargement therein and suitably formed at each end for connection with a saddle and weighting means, respectively.

25. 3. In a drawing frame or like machine, a top-roll weighting means comprising a stirrup formed of a rod bent at its opposite ends for attachment to the top roll and the weight, respectively, and formed with an enlargement at an intermediate point, in combination with a roller beam having an aperture accommodating the said rod and adapted to support the stirrup by its enlargement when disconnected from the top roll.

40. 4. In a drawing frame or like machine, a top-roll weighting means comprising a stirrup formed of a rod bent at its opposite ends for attachment to the top-roll and the weight, respectively, and formed with a flat enlargement at an intermediate point, in combination with a roller beam having an oblong aperture therein through which one end of said stirrup may be passed when putting the stirrup in position, the said enlargement and aperture being disposed transversely to each other and the former at 45 a distance above the latter when the stirrup

is in its normal weight-transmitting position.

5. In a drawing frame or like machine, the combination of the top drawing rolls, a saddle thereon, a weighted stirrup formed 55 at its upper end to embrace the saddle, a roller beam having an aperture accommodating the said stirrup, an enlargement on said stirrup above the aperture, said enlargement providing a stop shoulder to 60 sustain the stirrup on the beam and being disposed on the stirrup in position to form a purchase bearing for a lever fulcrumed on the roller beam.

6. In a drawing frame or like machine, 65 the combination with a roller beam having an oblong slot therein, a stirrup having its ends bent to form attachment means and one of said ends being adapted to pass through the aperture, a washer plate on the 70 stirrup adapted to cover the aperture, and an enlargement on the stirrup adapted to rest on the washer plate.

7. In a drawing frame or like machine, top-roll weighting means comprising in 75 combination with an apertured roller beam, a stirrup passing through the aperture therein and connected both above and below the said aperture with the top roll and weight, respectively, said stirrup having an 80 apertured enlargement normally sustained a slight distance above the surface of the roller beam when the stirrup is in its normal weight-transmitting position, the said aperture being faced forwardly and unobstructed, whereby a lever may be inserted therein to fulcrum against the surface of the roller beam to relieve the pressure on the top roll and the relative proportions of said 85 enlargement and roller beam aperture being 90 such as to sustain the weight when the stirrup has been disconnected from the top roll.

In testimony whereof, I have signed this specification in the presence of two witnesses.

HUGH S. FERGUSON.
